UNITED STATES PATENT OFFICE.

JOSEPHUS T. WILLIS, OF MERIDIAN, MISSISSIPPI.

SLICING-MACHINE.

1,318,038.

Specification of Letters Patent.

Patented Oct. 7, 1919.

Application filed March 12, 1919. Serial No. 282,067.

To all whom it may concern:

Be it known that I, JOSEPHUS T. WILLIS, a citizen of the United States, residing at Meridian, in the county of Lauderdale and State of Mississippi, have invented certain new and useful Improvements in Slicing-Machines, of which the following is a specification.

This invention relates to cutters for meats, 10 vegetables and the like, and more especially to those which reciprocate; and the object of the same is to produce a machine or implement for kitchen use by means of which meat such as bacon or sausage or vegetables 15 such as potatoes may be cut into slices or the slices thereof bisected.

A further object is to provide a machine of this kind wherein an ordinary meat or bread knife can be used or a fixed blade, the 20 former moving through the article being cut and the latter being stationary and the article moving with reference thereto.

Details are set forth in the following specification and claims, and attention is 25 drawn to the drawings, wherein—

Figure 1 is a plan view and Fig. 2 a side elevation of one form of this invention.

Fig. 3 is a longitudinal section thereof and Fig. 4 an end view. 30 Fig. 5 is a cross section showing part of the same structure, but with the use of a stop block, whereby an ordinary table knife blade may be used as the cutter.

Fig. 6 is a perspective detail of a part of 35 the block and the filler sheets or strips.

The bed 1 is by preference a block of wood or the like notched in one end as at 2 and carrying upon its upper surface a track composed of two L-shaped rails 3 running 40 lengthwise of the bed and spaced from each other about the width of the notch. Between one end of these rails is a stop block 4 fixed on the bed. At their other ends these rails are carried upward into split coils 5 45 which stand on opposite sides of the notch 2 and are intended for the removable insertion of a blade 6 whose cutting edge 7 when in place stands about over the inner end of the notch 2 as seen in Fig. 3. Coacting with 50 the structure thus far described is a base block 10 and a series of filler sheets or strips 11 of paper, cardboard or the like, these being of a size to fit closely between the rails and between the stop block 4 and the inner 55 end of the notch 2, and the base block 10 being of a size to rest upon them and to fit also

in place as seen in Fig. 5. The upper face of the base block is by preference corrugated longitudinally as shown at 12. In Fig. 5 is also shown a stop block 13 corrugated on its under face as at 14 and this may be sometimes employed as described below.

It will be noted that the rails 2 have inwardly struck tongues 9 which engage in the rear of the base block 10 and also the filler 65 strips 11 as shown in Figs. 3 and 4 whereby the base block and filler strips will be held against displacement over the notch 2. It will further be noted that the blade 6 is provided with outstanding lugs 6' these lugs 70 engaging forward of the split coils 5 and preventing rearward displacement of the blade when an article being cut is drawn across its upper surface.

In the use of this device for cutting vegetables, as for instance potatoes, the blade is inserted in the split coils 5 and is held fixedly but removably. The base block 10 is then placed between the two rails 3, and beneath it are inserted filler strips 11 sufficient in number to bring the upper face of this base block up nearly to a line flush with the upper edges of the rails 3. The potato is now laid upon the corrugated surface 12 of this block and moved quickly across the 85 blade 6. The result is that the cutting edge 7 of the blade severs a slice off the bottom of the potato, and the slice passes beneath the blade and drops into the notch 2. The potato is now retracted and again moved forward, and a second slice follows the first excepting that it has none of the potato peeling elsewhere than around its edge, the first slice having been cut off the exterior of the potato. The latter is now rapidly reciprocated along the corrugated surface of the block with the result that it is quickly cut into slices which fall through the notch into a receptacle in case the bed is mounted upon or above such a receptacle as will be clear. 90 95 100

When the device is to be used for slicing articles which are already thin, as for instance a slice of bacon, the blade 6 is removed and an ordinary knife blade (not shown) is employed. The base block 10 105 and its filler strips are again used, but the top block is corrugated on its face 14 and is now employed as shown in Fig. 5. The strip of bacon or the like is laid upon the upper face of the base block and borne down 110 upon it by the lower face of the top block, and while being so held the knife blade is

moved longitudinally over the upper edges of the rails 3 and it will slice or cut quite a thin slice of bacon into two yet thinner slices in a manner which will be clear.

5 The foregoing description and the drawings have reference to what may be considered the preferred, or improved form of my invention. It is to be understood that I may make such changes in construction and arrangement and combination of parts, materials, dimensions, et cetera, as may prove expedient and fall within the scope of the appended claims.

Having thus fully described my invention, 15 what I claim as new and desire to secure by Letters Patent is:-

1. In a device of the character described, the combination of a body, parallel rails fixed upon said body to form a track, a stop block carried by said body between the rails at one end of the track, tongues struck inwardly from said rails, cutting means supported upon said rails, a base block fitting between said rails, and filler strips posi-

tioned below said base block, whereby said base block and said filler strips will be held against displacement by said rails, said stop block and said tongues, as and for the purposes set forth.

2. In a device of the character described, the combination of a base block having a track thereon consisting of L-shaped rails, said track having extensions on each rail in the form of a split coil, a knife blade resting upon said rails and being received by said split coils, said knife blade having lugs extending outwardly from its ends and being positioned in front of said split coils, whereby said knife blade will be held against rearward displacement when an article being 40 cut is being moved thereacross.

In testimony whereof I affix my signature in presence of two witnesses.

JOSEPHUS T. WILLIS.
